UNITED STATES PATENT OFFICE

2,411,376

REFRIGERANT EVAPORATOR

Bernard C. Johnson, Mundelein, Ill., assignor to
Houdaille-Hershey Corporation, Detroit, Mich.,
a corporation of Michigan

Application March 16, 1944, Serial No. 526,665

11 Claims. (Cl. 62—126)

1 This invention relates to a refrigerant evaporator, and more particularly to an L-shaped evaporator for assembly in a refrigerator box or the like. The invention also relates to a combination with a refrigerator box, or the like, of one or more L-shaped evaporators for defining with the walls of said refrigerator box quick-freeze compartments, frozen food compartments and the like.

In accordance with the principles of my invention, I provide a standardized evaporator unit that is L-shaped in end view. Such an evaporator unit can be readily formed from metal sheets stamped to provide refrigerant flow passages, headers or the like. After assembly, the resulting flat unit is bent into L-shape with flanges turned up on the ends of the legs of the L for attachment to the walls of a compartment to be refrigerated, such as a refrigerator box. A single such unit can be mounted in a refrigerator box in such a way as to define a quick-freeze compartment for receiving ice trays. Alternatively, a pair of such L-shaped units may be attached to the top and sidewalls of the refrigerator box in a back-to-back relation, but with a space therebetween that can be utilized for the storage of tall bottles of milk and other liquids; one of the units being used for ice freezing and the other for frozen foods. In still a further modification, the space formed between the two units may be used as a frozen food compartment by placing refrigerated flat plate-like units at the top and bottom spaces. Where two or more units are used, the units can be connected for refrigerant flow therebetween.

It is therefore an important object of this invention to provide a standardized type of evaporator unit formed of a plurality of stamped sheets to provide the refrigerant flow passages, headers or the like, the resulting sheet-like unit being then bent into L-shape and provided with attaching flanges, whereby the unit, or a plurality of such units, can be readily positioned within a refrigerator box or the like to provide suitable quick-freeze chambers, frozen food compartments or compartments for other purposes.

Other and further important objects of this invention will be apparent from the disclosures in the specification and the accompanying drawings.

On the drawings:

Figure 1 is a fragmentary, vertical sectional view of a refrigerator box illustrating the manner of positioning and attaching an L-shaped evaporator unit of my invention;

Figure 2 is a similar, fragmentary, vertical sec-

tional view of a refrigerator box illustrating a pair of such evaporator units positioned therein;

Figure 3 is a similar, fragmentary, vertical sectional view of a refrigerator box illustrating a pair of such L-shaped evaporator units, together with several plate-like evaporator units, so positioned as to provide a pair of quick-freeze chambers and an intermediate frozen food chamber;

Figure 4 is an elevational side view of an evaporator unit of my invention;

Figure 5 is an enlarged, end elevational view of the unit illustrated in Figure 4; and

Figure 6 is a top plan view on a reduced scale of the evaporator unit in its flat, sheet-like form, prior to being bent into L-shape and prior to the flanges being formed on the end edges thereof.

The reference numeral 10 indicates generally a refrigerator box or housing. While the invention will be explained by reference to a refrigerator box, it will be understood that the invention is equally applicable to a refrigerated room or other chamber. Said refrigerator box 10 is illustrated in its conventional form as having an upper or top wall 11 and sidewalls 12 and 13, together with a back wall 14. As viewed in Figures 1 to 3, inclusive, the viewer is looking into the refrigerator toward the back wall 14.

In Figure 1 there is illustrated an arrangement in which a single L-shaped evaporator unit 15 is positioned in the refrigerator box 10 in an upper corner thereof to define a quick-freeze chamber, indicated generally by the reference numeral 16. Said evaporator unit 15 is provided with a vertical leg 17 having a flange 18 extending along its upper edge that is attached to the upper wall 11 by an attaching means 19. The horizontal leg 20 of said evaporator unit is provided with an upturned flange 21 through which attaching means 22 extend into the side wall 12 of the box. A vertically extending plate 23 is also supported from the attaching means 22 and serves to support one side of a horizontal shelf 24. The other side of the shelf 24 may be brazed or otherwise secured, as at 25, to the vertical leg 17 of the evaporator unit 15. The purpose of the shelf 24 is, of course, to support ice trays (not shown).

In Figure 2, a pair of evaporator units 15 are illustrated as positioned in a refrigerator box 10 to provide a pair of quick-freeze compartments 16 and 16a. Each of the evaporator units 15 is of identical construction. The L-shape of the evaporator units 15 lends itself to cooperation with the walls of the refrigerator box to define therewith quick-freeze chambers, and by placing the two evaporator units in back-to-back

relationship, as illustrated in Figure 2, a space 26 is left between said evaporator units for any desired purpose, such as for use as a food and bottle compartment. In Figure 2, a wire shelf 27 extends horizontally beneath the evaporator unit 15 to form a support for food placed in the space 26.

In Figure 3, further provision for refrigerating the space 26 is shown. A flat, plate-like refrigerator unit 28 is attached by means of upturned flanges 29 to the L-shaped evaporator units 15, adjacent the bends therein. The plate-like evaporator unit 28 thus serves as a bottom wall for the space 26. In addition, a second plate-like evaporator unit 30 is positioned adjacent the top wall 11 and supported at its ends from the same attaching means 19 that serve to support the upper ends of the L-shaped evaporator units 15. Other plate-like evaporator units 31 may be mounted as shelves to give additional refrigerating capacity in the quick-freeze chambers 16 and 16a.

Before describing the arrangement for refrigerant flow shown in Figures 1 to 3, inclusive, the construction of one of the L-shaped evaporator units 15 will be explained. The fundamental construction of all of the evaporator units is substantially the same. As illustrated in Figure 6, an evaporator unit 32 is initially formed by joining together a pair of co-extensive sheets of metal stamped to provide transversely extending headers 33 and 34 and connecting refrigerant flow passages 35. The header 34 may be a compound header comprising an inner header portion 36 and an outer header portion 37 parallel thereto and in flow communication therewith around one end, as at 38. A further communication between the header portions 36 and 37 may be provided intermediate their lengths, as at 39. The outer header portion 37 extends to an edge of the sheet to afford a connection 40 for the refrigerant piping.

The ends of the plate-like evaporator unit 32 are flat, the headers 33 and 34 lying well inside the end edges of the plate. Apertures 41 are provided in the flat marginal portions for receiving attaching means such as the means 19 previously described.

As illustrated in Figure 5, the flat marginal portions are turned up to provide end flanges 42 and 43. Either before or after the bending of the flange portions 42 and 43, the plate 32 is bent into L-shape, as by forming a smooth bend 44. Nipples 45 and 46 are suitably attached to the outlets of the manifolds 34 and 33. The evaporator unit 15 is then in its finished condition ready for installation in any of the manners illustrated in Figures 1 to 3, inclusive.

As illustrated in Figure 1, the refrigerant enters the evaporator unit 15 through the nipple 48 into the header 33, from which it passes through the passages 35 to the compound header 34. The purpose of dividing the compound header 34 is to eliminate the liability of liquid refrigerant passing out through the nipple 45, or, in other words, to insure complete evaporation of the liquid refrigerant within the evaporator unit 15.

In Figure 2, the refrigerant system includes inlet piping 48, from which extend branch piping 49 and 50 to the two evaporator units 15. The compound headers 34 of said evaporator units 15 are connected by piping 51, from which a pipe 52 leads to the condenser-compressor unit (not shown).

In Figure 3, a somewhat more complicated refrigerating system is illustrated. In this arrangement, an inlet pipe 54 is connected directly to the plate-like evaporator 28. The outlet of said plate-like unit 28 is connected by means of a pipe 55 to the inlet side of the other plate-like unit 30. After flowing through the unit 30, the refrigerant passes out through a pipe 56 and through branch piping 57 and 58 to the shelf-type units 31. Short pipes 59 and 60 connect said shelf units 31 to the L-shaped units 15. The headers 34 of said unit 15 are connected by means of a pipe 62 and a return pipe 63 to the condenser-compressor unit.

Various other refrigerant circuits could be employed than those here illustrated. The important thing is that my standardized L-shaped evaporator unit lends itself to ready adaptation in forming either one or a plurality of quick-freezing compartments, frozen food chambers or the like. These different arrangements can be easily fabricated from L-shaped evaporator units, with or without the use of plate or shelf-type units. As a result, the number of different styles of evaporator units and of sizes in each style can be greatly reduced.

It will, of course, be understood that various details of construction may be varied through a wide range without departing from the principles of this invention and it is, therefore, not the purpose to limit the patent granted hereon otherwise than necessitated by the scope of the appended claims.

What I claim is:

- 35 1. In combination, a refrigerator box, an evaporator unit of L-shape and having integral apertured end flanges, and means passing through said apertured end flanges for attaching said evaporator to adjacent walls of said refrigerator box.
- 40 2. In combination, a refrigerator having top and sidewalls, an evaporator unit of sheet-like construction and L-shaped in end view, said unit having integral flanges provided with apertures, and means extending through said apertures into said walls to attach said unit thereto.
- 45 3. In combination, a refrigerator having top and sidewalls, a plurality of L-shaped, sheet-like evaporator units, each unit having flanges for attachment to said walls, and means attaching said units through said flanges to said top and sidewalls.
- 50 4. In combination, a refrigerator having top and sidewalls, a plurality of L-shaped, sheet-like evaporator units, each unit having flanges for attachment to said walls, and means attaching said units through said flanges to said top and sidewalls, each unit defining with the wall portions spanned thereby a quick-freeze chamber.
- 55 5. In combination, a refrigerator having top and sidewalls, a pair of evaporator units in refrigerant flow communication with each other, each of said units being L-shaped and being connected at its ends to a top and a sidewall to define therewith a food and bottle chamber.
- 60 6. In combination, a refrigerator having top and sidewalls, a pair of evaporator units in refrigerant flow communication with each other, each other, each of said units being L-shaped and being connected at its ends to a top and a sidewall to define therewith a quick-freeze chamber and a refrigerated plate joined to the backs of said L-shaped units to define therewith and with the top wall a frozen food compartment.
- 65 7. In combination a refrigerator having top

and sidewalls, a pair of evaporator units in refrigerant flow communication with each other, each of said units being L-shaped and being connected at its ends to a top and a sidewall to define therewith a quick-freeze chamber and a refrigerated plate joined to the backs of said L-shaped units to define therewith and with the top wall a frozen food compartment, said plate having refrigerant flow passages in flow communication with said pair of evaporator units.

8. In combination, a refrigerator box having a top and sidewalls, a pair of L-shaped evaporator units secured to said walls in spaced back-to-back relation to each other and defining with said walls quick-freeze compartments.

9. In combination, a refrigerator box having a top and sidewalls, a pair of L-shaped evaporator units secured to said walls in spaced back-to-back relation to each other and defining with said walls quick-freeze compartments and shelves 20 in said compartments for supporting ice trays.

10. In combination, a refrigerator box having a top and sidewalls, a pair of L-shaped evaporator units secured to said walls in spaced back-to-back relation to each other and defining with 5 said walls quick-freeze compartments, a refrigerant inlet pipe branched for connection with the lower ends of said units and a refrigerant outlet pipe branched for connection with the upper ends of said units.

11. In combination, a refrigerator having a top and sidewalls, a pair of sheet-like evaporator units, each L-shaped in end view and connected to the top and a sidewall to define therewith a quick-freeze chamber and to leave a space 15 between said units, a pair of horizontally disposed plate-like evaporator units positioned at the top and bottom of said space between said first units, and refrigerant flow conduits connecting all of said units.

BERNARD C. JOHNSON.
